UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed September 11, 1925. Serial No. 55,669.

This invention relates to typographical distributing machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through distributing mechanism to the magazine from which they started. More particularly, it relates to that style of machine equipped with a plurality of magazines containing matrices of different fonts which may be used together in the composition of mixed matter, as for example the commercial linotype model 9 or model 25. In these machines the distributing mechanism ordinarily comprises a font separator or primary distributor and a plurality of main or secondary distributors, whereby the matrices are first sorted according to font and thereafter separated according to character and restored to the proper channels of their respective magazines.

The present invention is directed principally to certain improvements in the primary distributor, intended to facilitate the handling of thin matrices and to obviate some of the difficulties which have heretofore arisen in connection with them. As is well known, the primary distributor generally includes a ribbed bar formed at different points in its length with matrix releasing or blank portions, a set of rotary screws for advancing the matrices onto and along the bar as they are detached from the composed line by the usual lifting finger, and a plurality of different selector bridges located directly beneath the blank portions of the bar and adapted to cooperate with differently located notches formed in the bottom edges of the advancing matrices in effecting their separation according to font. In the normal operation of the parts, a matrix, when raised by the lifting finger, is immediately picked up by the screws and carried onto and along the ribbed bar until

its distinguishing notch registers with one of the selector bridges, at which time it is allowed to drop to a slightly lower level out of engaging relation to the bar and finally fall into one of several chutes leading to the main distributors. It has been found in practice that the matrices, particularly those of the thinner variety, frequently fail to drop astride their corresponding bridges as they should but, instead, travel past the bridges and drop into the wrong chute and thus enter the wrong magazine or else leave the machine without being distributed at all. This condition which has been aggravated by the increased speed of distribution resulting from the use of the modern high pitch screws, occurs most frequently at the first bridge, due to the close proximity of the latter to the pick-up zone of the matrices which are still in an unstable condition when they reach the bridge.

According to this invention, means are provided tending to retard the matrices as they reach the first bridge and to urge them downward as they cross it. In the preferred embodiment illustrated, such means comprise a pair of dogs pivotally mounted on opposite sides of the ribbed bar near its receiving end and arranged to yieldingly engage the advancing matrices at their upper ends.

The invention also contemplates means for regulating the initial purchase of the lifting finger on the bottom edges of the matrices to ensure the proper delivery of thin matrices to the conveying screws.

In the accompanying drawing, the invention has been shown only in preferred form and by way of example, and as applied to the specific style of distributing mechanism indicated. However, many changes and variations may be made therein and in its mode of application, which will still be comprised within its spirit. It should be understood therefore that the invention is not limited to any specific form or embodiment, except in so far as such limitations are specified in the claims.

In the drawings:
Fig. 1 is a rear elevation, partly in section and broken away, of the primary distributor of a linotype machine equipped with the present improvements;

Fig. 2 is an enlarged transverse section taken on the line 2—2 of Fig. 1, showing a matrix as displaced by the dogs; and

Fig. 3 is a detail horizontal section taken on the line 3—3 of Fig. 1.

In machines of the present class, a composed line of matrices X , after the casting operation, is lifted to the primary distributing level, where it is shifted horizontally by a transfer slide Q into a distributor box A , the pusher block Q^1 of said slide serving to hold the line yieldingly against stop shoulders A^1 formed on the box guide rails and arranged to engage the projecting ears X^1 of each leading matrix until the last one in the line has been distributed. The box A is equipped as usual with a reciprocating finger A^2 pivotally connected to one end of a rocking lever A^3 so as to feed the matrices one at a time to the primary distributor B , the latter comprising the ribbed bar B^1 , the matrix conveying screws B^2 , and the associated selector bridges B^3 . As shown in Fig. 1, the rocking lever A^3 is spring-controlled and receives its motion from a cam B^6 fastened to one of the screw spindles through the vertical slide rod A^4 and roller A^5 . A transverse block A^6 against which the lifting finger A^2 is normally held by a light pull spring A^7 serves, as heretofore, to guide the finger in its reciprocations and determines its purchase on the bottom edges of matrices to be lifted. The primary distributor B herein illustrated is designed for a two magazine mixing machine and hence only two selector bridges B^3 are employed.

These bridges are located directly below blank portions B^4 , B^5 of the bar B^1 , so as to underlie the advancing matrices, and are formed with small tongues B^7 arranged to support matrices of one form at the proper level to reengage the bar and permit those of another form to drop below said level to disengage the bar. Short rail sections B^8 , B^9 are arranged to temporarily sustain the matrices by their upper projecting ears as they drop astride the tongues B^7 . As will be noted in Fig. 1, these rail sections terminate above the open ends of a pair of chutes C , C^1 , which conduct matrices released by the rails to the two main distributors (not shown). With this arrangement and under normal conditions, matrices in course of distribution will either straddle the tongues B^7 of the selector bridges as they pass across the blank portions B^4 , B^5 , of the ribbed bar, or be sustained thereby until they reengage the bar, depending, of course, upon the location of the distinguishing notches X^2 . Thus, an advancing matrix belonging to a certain font and whose distinguishing notch registers with the tongue B^7 of the first bridge is allowed

to drop below the bar engaging level (Fig. 2), while, on the other hand, a matrix of a different font, whose notch does not register with said tongue, will be supported by the latter across the gap B^4 at the proper level to reengage the bar. These parts and their mode of operation are so well known that any further description would be superfluous.

In carrying out the present invention, there is provided a pair of gravity dogs D pivotally mounted on opposite sides of the bar B^1 and arranged to engage the upper ends of the advancing matrices as they approach the first selector bridge. These dogs at their free ends are each formed with a head portion D^1 having a beveled nose D^2 disposed in the path of the advancing matrices, and a lip D^3 normally resting upon a pin D^4 extending transversely from the bar. A sheet metal keeper plate D^5 , fastened about midway of the dogs to the top of the bar B^1 , serves to restrain the dogs against lateral displacement. According to this arrangement, a matrix picked up by the screws B^2 and whose font notch X^2 coincides with the tongue B^7 of the first selector bridge, will be urged downwardly by the dogs D , so as to straddle the tongue in the desired manner. Preferably these dogs are of like form and weight so that an even pressure, although very slight and in fact just enough to be effective, will be exerted upon the upper ends of the matrices to place them squarely astride the bridge tongue. In this connection, it is pointed out that the location of the pins D^4 is such that the pressure of the dogs will cease after the matrices are pushed downwardly over the bridge tongue a slight extent and before the matrices become supported by the rail sections B^8 and the upper face of the bridge (see Fig. 2). Furthermore, the form and arrangement of the dogs D are such that, besides functioning in the manner just described, they also serve to retard and stabilize the matrices as they approach the first bridge from the nearby pick-up position, it being appreciated that the matrices when picked up from a position of rest by the rapidly rotating high pitch screws are subjected to a violent disturbance which may not have subsided by the time they reach the bridge. While a selecting tongue B^7 is herein shown on the bridge located below the second blank portion B^5 , its presence is not necessary, as the dogs D will positively ensure the deposit of all matrices into the chute C destined for the corresponding magazine, leaving the other matrices free to be dropped into the chute C^1 for return to the second magazine. However, the use of the tongue will prevent the delivery into the chute C^1 of misplaced matrices or matrices belonging to foreign fonts, such mat-

rices being carried off by the ribbed portion B¹⁰ and dropped onto the rail sections B¹¹ which discharge them into the pi-tray or receptacle E. It will be understood that 5 matrices whose notches X² do not register with the tongue B⁷ of the first selector bridge will be maintained at the higher level for re-engagement with the ribbed bar, the dogs D in such cases yielding upwardly to 10 permit the matrices to pass by (see dotted lines in Fig. 1), although still exerting a desirable retarding influence thereon. If desired, a second pair of dogs D may be employed for the second selector bridge, or in 15 cases where there are more than two bridges, one pair for each.

According to another feature of the invention, the lifting finger A² is controlled in such manner that its purchase on the bottom edges of the matrices may be readily and accurately regulated as required, it being noted that the amount of purchase, although necessarily less than the thickness of the thinnest matrix should always be as great as possible in order to prevent slipping of the finger from under the matrices during lifting. As shown in Figs. 1 and 3, the block A⁶, instead of constituting a fixed part of the box A, as heretofore, is slidably mounted between the side walls thereof and loosely connected or swiveled, as at A⁸, to one end of an adjusting screw A⁹, which has a finely threaded bearing in a block A¹⁰ fixed to the box walls. In order to lock or 25 maintain the guide block A⁶ in its adjusted positions, it is provided with a pair of clamping screws A¹¹ slidably arranged in elongated slots A¹² formed in the opposite side plates of the box (see Fig. 3). As a result of this arrangement (since the finger A² is constantly held by the spring A⁷ up against the guide block A⁶) the desired adjustment of the finger may be quickly and easily effected by turning the adjusting screw A⁹ in one direction or the other, the clamping screws A¹¹ being loosened and tightened before and after the adjusting operation, respectively. In this way, the feeding of the thinner matrices to the primary distributor is greatly facilitated.

Having thus described my invention, its construction and mode of operation, what I claim and desire to secure by Letters Patent of the United States is as follows:

1. In a typographical distributing mechanism, the combination of a ribbed bar, a set of high-pitched screws for advancing the matrices along the bar, means for feeding the matrices one at a time into position to be picked up by the screws, and means arranged adjacent to the pick-up zone to engage the advancing matrices at their upper ends and tending to retard them in their advance.

2. In a typographical distributing mech-

anism, the combination of a ribbed bar, a set of screws for advancing the matrices along the bar, means for feeding the matrices successively to the screws, a selector bridge to cooperate with the advancing matrices, and yielding means arranged to engage the upper ends of the advancing matrices and exert a downward pressure thereon as they cross the bridge.

3. In a typographical distributing mechanism, the combination of a ribbed bar, a set of screws for advancing the matrices along the bar, means for feeding the matrices successively to the screws, a selector bridge to cooperate with the advancing matrices, and a pair of yielding dogs arranged in the path of the matrices and tending to press them downward as they cross the bridge.

4. In a typographical distributing mechanism, the combination of a ribbed bar formed with matrix releasing or blank portions, a set of screws for advancing the matrices along the bar, a plurality of selector bridges arranged beneath the blank portions of the bar, and means arranged in the path of advancing matrices and tending to retard them as they approach the first bridge and to urge them downward as they cross it.

5. In a typographical distributing mechanism, the combination of a ribbed bar formed with a blank portion, a set of screws for advancing the matrices along the bar, a selector bridge arranged beneath said blank portion, a pair of vertically movable dogs pivotally mounted on opposite sides of said bar and arranged to yieldingly engage the upper ends of the matrices as they cross the bridge, and stop pins adapted to limit the downward movement of the dogs.

6. In a typographical distributing mechanism, the combination of a distributor box through which the matrices are transferred for distribution, stop shoulders for arresting the matrices within the box, a reciprocating finger for lifting the matrices successively above said shoulders, an adjustable block for guiding the finger in its reciprocations, and means for adjusting the block to regulate the purchase of the finger on the bottom edges of the matrices to be lifted.

7. In a typographical distributing mechanism, the combination of a distributor box, a reciprocating finger associated therewith, an adjustable block for guiding the finger in the reciprocations, means for adjusting the block laterally in either direction and means for retaining the block in its adjusted positions.

8. In a typographical distributing mechanism, the combination of a distributor box, a reciprocating finger associated therewith, an adjustable block for guiding the finger in the reciprocations, a stationary block

- mounted adjacent the adjustable block and an adjusting screw threaded to the stationary block and swiveled to the adjusting block.
- 5 9. In a typographical distributing mechanism, the combination of a distributor box, a reciprocating finger associated therewith, an adjustable block for guiding the finger in its reciprocations, a stationary block
- 10 mounted adjacent the adjustable block, an adjusting screw threaded to the stationary block and swiveled to the adjusting block, and a clamping screw threaded to the adjustable block and arranged to bear against a relatively fixed part to hold the block in its adjusted position.
10. In a typographical distributing mechanism, the combination of a ribbed bar, a set of screws for advancing the matrices along the bar, means for feeding the matrices successively to the screws, a selector bridge to cooperate with the advancing matrices, and yielding means arranged to engage the upper ends of the advancing matrices and exert a downward pressure thereon as they cross the bridge, said means ceasing their pressure upon the matrices when the latter drop astride the bridge. 20 25

In testimony whereof, I have affixed my signature hereto.

DAVID S. KENNEDY.
